UNITED STATES PATENT OFFICE.

HERMANN JAWORSKI, OF NEW HAVEN, CONNECTICUT, ASSIGNOR TO
SARGENT & CO., OF SAME PLACE.

DESIGN FOR A BRACKET.

SPECIFICATION forming part of Design No. 12,245, dated May 3, 1881.

Application filed March 28, 1881. Term of patent 14 years.

To all whom it may concern:

Be it known that I, HERMANN JAWORSKI, of New Haven, in the county of New Haven and State of Connecticut, have invented a new 5 Design for Brackets; and I do hereby declare the following, when taken in connection with the accompanying drawing and the letters of reference marked thereon, to be a full, clear, and exact description of the same, and which 10 said drawing constitutes part of this specification, and represents in the figure a side view. This invention relates to a design for brackets, such as made from cast metal, and intended for a support for shelves, &c.; and the invention 15 consists in the configuration, as herein-after described, and shown in the accompanying illustration.

A represents the back, and B the arm extending at right angles therefrom; C, a diagonal brace extending from the back up to the

arm. Midway between the points of connection is a rose-shaped ornament, D. Between the brace C and the angle is a second brace, E, of quadrant shape. The space between the two braces is represented as filled by a lattice-work ornamentation; but this ornamentation may be changed without departing from the design. 25

I claim—

The design for bracket, consisting of the 30 back and arm with the diagonal brace extending from the back to the arm, and a quadrant-shaped brace between the diagonal brace and the angle, as shown in the accompanying illustration.

HERMANN JAWORSKI.
